UNITED STATES PATENT OFFICE.

ROBERT V. BINGAY, OF PITTSBURGH, PENNSYLVANIA, ASSIGNOR TO PITTSBURGH
TRANSFORMER COMPANY, A CORPORATION OF PENNSYLVANIA.

RADIATOR.

Application filed March 31, 1921. Serial No. 457,282.

To all whom it may concern:

Be it known that I, ROBERT V. BINGAY, a citizen of the United States, residing at Pittsburgh, in the county of Allegheny and State of Pennsylvania, have invented certain new and useful Improvements in Radiators, of which the following is a specification.

This invention relates to radiators and particularly to radiators for circulating and cooling a fluid, such as the oil of an oil cooled transformer tank or the like. The object of the invention is to provide a radiator that will be simple and inexpensive in formation and durable in service having the radiating surfaces exposed at all points so as to avoid the accumulation of moisture in inaccessible recesses and the resultant rusting and weakening of the radiator walls. Further objects of the invention in making the radiator light in weight and at the same time strong and self supporting, will appear from the following specification taken in connection with the accompanying drawings, in which—

Fig. 1 is a plan view of a main tank provided with auxiliary radiator tanks illustrating one embodiment of the invention.

Fig. 2 is a horizontal sectional view 30 through one of said radiators.

Fig. 3 is a vertical sectional view of the same.

Fig. 4 is a perspective view of an upper portion of a radiator, showing a modified detail.

Fig. 5 is a view similar to Fig. 1 but illustrating a modification.

Fig. 6 is a vertical sectional view of the radiator shown in Fig. 5.

Fig. 7 is a horizontal sectional view of the radiator shown in Fig. 5, and

Figs. 8, 9 and 10 are elevational views illustrating methods of connecting the radiators to the main tank.

In the specific embodiment of the invention shown in Fig. 1 a main tank T containing, for instance, transformer coils and core immersed in oil, is provided with radiators R connected to the tank T at the top and bottom to circulate the oil downward in contact with the cooling surfaces of the radiators. The radiators R may be connected in a single series partially or wholly around the tank, for instance, as shown on the right side of Fig. 1 and there

may be a number of series of radiators at different radial distances from the tank so as to be staggered with relation to each other, for instance, as shown to the left in Fig. 1. Each radiator (as shown in Figs. 2-4) comprises a body portion 10 in the form of an extended deeply corrugated tank with upper and lower connections to the main tank T. The body portions 10 are formed by notching steel sheets at the upper and lower edges and bending said sheets into corrugations 11 with the bottoms of the notches at their outer ends 12 and the spaces between the notches at their inner ends 13. The meeting edges of the sheets 14 for instance, at 14 are turned over to form a V shaped groove between them and are welded together along this groove. With the body thus formed into generally cylindrical shape (Figs. 1-4) the edges of the notches then form inclined edges 15 between outer ends 12 and inner ends 13 of the corrugations and by flattening outward the edges of ends 13 the inner ends of edges 15 are brought together. The remainder of 80 these edges 15 are then turned over to meet along a line and are welded together as shown. Each corrugation 11 is rigidly arched over at its ends and protrudes outward with its surfaces exposed. The flattened inner ends 13 form beveled rings at each end of the body 10 and into these the pipes 20 are set and welded along the line 21 to form a strong air-tight union. The pipes 20 may be bent inwardly as shown and 85 provided with flanges 22 to be bolted to the flange 23 of the pipe section 24 welded into the side of the tank. Instead of the bent pipes 20 the cylinder 20' may be used as shown in Fig. 4 with a removable cap 25 and 90 a separate connecting pipe 26, this construction being used at the top or bottom or both. The radiator is thus a single corrugated body bent and welded into a rigid self supporting unit in simple, inexpensive manner. There is no accurate machining or alining to be done and no delicate fitting of parts. The outer surfaces of the radiator are all exposed directly to the air circulation and easily accessible so as to be readily 100 inspected and kept coated against rust. All the surfaces tend to shed rain and moisture and there are no inaccessible corners catching moisture so as to rust and weaken. The cross sectional area is large and unitary so 110

that circulation is maintained free from stoppage and obstruction and at the same time a large cooling area is provided by the extended surfaces of the corrugations. Access to the interior for inspection and cleaning may be had by simply removing the radiator or caps 25 and this will give a single direct opening through the radiator.

The radiator may be of any desired shape, for instance, it may be generally rectangular in section as shown at R', in Figs. 5, 6 and 7 with corrugations 30 at the sides and 31 at the ends if desired. With this radiator the formation is the same as for that of Figs. 1 to 4, but the upper cylinders 20 will be replaced by rectangular frames 32 with covers 33 preferably removably clamped in place, and the lower end will have the bottom B welded in place along the line 34 and provided with drain cock 35. The upper pipe connection 43 is welded into the side of the frame 32 and the lower pipe connection 44 is welded into the side of the radiator body.

Where desired a plurality of radiators may be connected together as a unit to a common distributing pipe permitting the size and proportions of the unit to be widely varied by varying the number of radiators connected together. For instance in Figs. 8 and 9 three radiators R₂ are connected together to upper and lower pipes 45 which in turn are connected by pipes 47 to the source of fluid to be cooled. Each radiator R₂ has its cylinders 46 welded to the pipes 45 and the ends of this pipe are closed by removable plugs 47. In Fig. 10 the cylinders 27 of two radiators R₃ are connected by the intermediate pipe 48 which is connected to the fluid supply by pipe 49.

The radiators are preferably supported by their pipe connections from the tank. Their formation of bent and welded sheet steel makes them light in weight with relatively large exposed surface and relatively small weight of oil in the radiator. At the same time each radiator is a rigid unit in which the parts are relatively self supporting. The deeply corrugated structure gives stiffness all around and the arched corrugations welded into integral rings at each end further reinforce the body and provide firm anchorage for the supporting connections.

I claim:

1. The combination with a tank containing a fluid to be cooled, of a radiator comprising a corrugated sheet body the ends of the corrugations being arched and welded to form a continuous end surface, pipe connections welded to the top end surface of the radiator and to the top of the tank respectively, and similar pipe connections at the bottom of the radiator and tank.

2. The combination with a tank containing a fluid to be cooled, of a radiator comprising

a corrugated sheet body bent to form an inner passage of generally circular form, the ends of the corrugations being arched and welded to form a continuous end surface, and pipe connections extending outwardly from the top and bottom of the tank and welded to the top and bottom end surfaces respectively of the radiator.

3. The combination with a tank containing a fluid to be cooled, of a plurality of radiators each comprising a corrugated sheet body, and pipe connections extending outwardly from said tank at the top and bottom thereof, to the top and bottom of each of said radiators respectively, said pipe connections for the several radiators differing in length whereby the radiators are positioned in staggered relation with respect to the tank.

4. The combination with a tank containing a fluid to be cooled, of a radiator comprising a vertically corrugated sheet steel body having a long relatively narrow central passage with channels extending outward therefrom between said corrugations, fluid circulating connections at the ends of said body comprising an extension conforming to the general shape of said passage and welded in place at the end thereof, and a removable closure for the end of said extension giving access to the interior of said radiator.

5. The combination with a tank containing a fluid to be cooled, of a radiator comprising a corrugated sheet body bent to form an inner passage of generally circular form, the ends of the corrugations being arched and welded to form a continuous end surface, cylindrical fluid circulating extensions welded to the top and bottom end surfaces respectively of said radiator, and pipe connections from said top and bottom extensions to the top and bottom of the tank respectively.

6. The combination with a tank containing a fluid to be cooled of a radiator connected to said tank by top and bottom pipes, the radiator having a central passage approximately of equal cross sectional area to the cross sectional area of the connecting pipes, and outwardly radiating corrugations to form outwardly projecting sheets of fluid radiating from said central passage.

7. The combination with a tank containing a fluid to be cooled, of a radiator comprising a corrugated sheet body the ends of the corrugations being arched and welded to form a continuous end surface, pipe connections welded to the top end surface of the radiator and to the top of the tank respectively, similar pipe connections at the bottom of the radiator and tank, the said radiator being star shaped in cross section with a central passage approximately equal to the cross section of the pipe connections.

8. The combination with a tank containing a fluid to be cooled, of a radiator comprising a sheet metal body portion having outwardly extending corrugations with arch'd ends welded into a rigid ring at each end, and pipe connections from said tank adapted to support said radiator on said tank.
  9. The combination with a tank contain-
- ing a fluid to be cooled, of a radiating means 10 therefor, comprising a plurality of radiators connected together to said tank, each radiator comprising a corrugated body portion of sheet steel having an end extension with a removable closure giving access to the interior of the radiator. 15

ROBERT V. BINGAY.
